UNITED STATES PATENT OFFICE

133,706

DESIGN FOR A JEWELRY FINDING

Charles L. Thatcher, South Attleboro, Mass., assignor to Marathon Company, a corporation of Massachusetts

Application July 10, 1942, Serial No. 107,466

Term of patent 3½ years

To all whom it may concern:

Be it known that I, Charles L. Thatcher, a citizen of the United States of America, residing at South Attleboro, county of Bristol, State of Massachusetts, have invented a new, original, and ornamental Design for a Jewelry Finding, of which the following is a specification, reference being had to the accompanying drawing, forming a part thereof.

Fig. 1 is a top plan view of a jewelry finding showing my new design; and

Fig. 2 is a side elevational view thereof.

I claim:

The ornamental design for a jewelry finding, substantially as shown.

CHARLES L. THATCHER.
